COMBINED CIGARETTE CASE AND LIGHTER

Filed Aug. 28, 1936

UNITED STATES PATENT OFFICE

2,086,411

COMBINED CIGARETTE CASE AND LIGHTER

Irving Florman, New York, N. Y.

Application August 23, 1936, Serial No. 98,357

15 Claims. (Cl. 206—41.4)

My invention relates to a combined cigarette case and lighter, and particularly to a device of this nature in which the cigarette case and lighter are interconnected in a special manner.

5 The primary object of this invention is to provide a cigarette case having a lighter so mounted therein that the opening of the cigarette case ejects the lighter into a position where it may be operated to light a cigarette or the like. 10 More especially the arrangement is such that the cigarette case may be closed while leaving the lighter in ejected position, after which the lighter is manually returned to its position within the case. In the preferred form of the invention the 15 lighter is practically flush with the case when in its retracted position.

According to still another feature of this invention, the lighter is movable manually out of the case without the opening of the case, so that 20 it may be used for other purposes than the lighting of a cigarette taken from the case.

Still another object of the invention is to provide a simple and effective construction for accomplishing the above result.

25 Further objects and advantages will appear more fully from the following description particularly when taken in conjunction with the accompanying drawing which forms a part thereof.

30 In the drawing:

Fig. 1 is a side elevation showing the cigarette case closed with the lighter in ejected, operated position.

Fig. 2 is an end view of the same.

35 Fig. 3 is a cross section on the line 3—3 of Fig. 1.

Fig. 4 is a side elevation of the cigarette case with the lighter closed and in retracted position.

Figs. 5 and 7 are cross sections on the lines 40 5—5 and 7—7 respectively of Fig. 4.

Fig. 6 is a bottom view of the cigarette case.

The cigarette case proper is formed of a front section 2 and a rear section 4. These two sections together form a substantially rectangular box, of considerable length, of a height substantially equal to the length of a cigarette and of a thickness suitable to hold a cigarette. The two sections are hinged together along their top edges as at 6, and may be held in closed position by a catch 8 of any suitable construction, such as a spring catch.

In one end of the rear section 4 is arranged a channel-shaped element 10 of sheet metal, extending across the whole height of the case, and 50 of substantially the same thickness as the thick-

ness of the case. This member 10 thus forms at one end of the case a vertical channel or guide space. The top walls of the sections 2 and 4 are cut away at the top of the channel, while at the bottom a large hole 12 and a small hole 14 are 5 formed in the casing wall.

A cigarette lighter is mounted for vertical sliding movement within the channel formed by the member 10. This lighter may be, for example, of the type shown in my Patent No. 2,014,320, and 10 its details form no part of the present invention. It will be sufficient to state that the lighter includes a body portion or fuel chamber 16, which fits within the member 10, a cover 18 pivoted at 20 on the top of the fuel container, a snuffer 15 member 22, a flint wheel 24 and a wick 26. The flint wheel engages a flint which is mounted in the upper end of a tube 27 extending downwardly through the fuel chamber and which encloses a spring 29 for holding the flint in engagement with the flint wheel 24. This flint tube is 25 closed at its lower end by a plug 48. Upon the raising of the cover 18, a spring is placed under tension between the cover and the snuffer. When the cover approaches its open position, the snuffer, which has heretofore been held in depressed position, is released and raised by the spring. The upward movement of the snuffer turns the flint wheel to ignite the wick.

As has been stated, the fuel container or body 30 of the lighter is slidable in the channel 10. In order to move the lighter upwardly when the cigarette case is open, I provide in the inner wall of the channel 10 a vertical slot 28. A screw 30 fits in this slot and is threaded into the side wall 35 of the fuel container 16. The wall of the channel 10 is also provided with a slit 32 which communicates with the slot 28 and forms a thin narrow tongue 34 which is bent slightly into the slot 28. This member 34 acts as a resilient holding member, which will hold the lighter in raised position until sufficient force is supplied to overcome the resilient pressure of the tongue, whereupon the lighter may again move downwardly to its depressed position.

45 Within the cover member 2 and adjacent the wall of the channel 10 is arranged a plate 36. This plate supports a pin 38 on which is pivoted a lever 40, the lower end 42 of which is formed as a hook which extends beneath the screw 30. A 50 coil spring 44 passing around the pin 38 and engaging the wall of the casing and the lever urges the lever in the direction of the screw 30, so as to keep the lever normally engaged with this screw.

In the bottom of the fuel container 16 there are 55

provided two plugs. The plug 46 which is opposite the hole 12 serves for the filling of the container 16, while the plug 48 opposite hole 14 permits the removal and replacement of the flint 5 which engages the wheel 24.

It will be evident that while upward movement of the hook 40 will necessarily move the cigarette lighter upward, nevertheless the lighter can move upward alone with the movement of the hook. In order to permit such manual movement of the lighter, the cover 18 is provided at its sides with extensions or flanges 50 by which the lighter may be lifted upward manually into an operative position.

15 The operation of the device is as follows: When a cigarette is to be removed from the case, the case is opened. The movement of the section 2 away from the section 4 obviously exerts a pull on the lever 40, tending to move it upward (Fig. 20 4). This upward movement through the screw 30 forces the cigarette lighter upward into the position shown in Fig. 1, the cover however being closed. The lighter is held in this raised position by the spring tongue 34. The cigarette case may 25 now be closed, the lever 40 during such closing movement sliding downwardly to its initial position but leaving the lighter in raised position. The user now pushes over the cover 18 with his thumb, and the wick is ignited so that the cigarette 30 may be lit.

When the lighter is no longer needed, the cover is closed and a downward pressure will be sufficient to overcome the spring action of the member 34 and restore the lighter to its position 35 within the case where its top edge is flush with the top edge of the case.

Obviously if the lighter is to be used alone it may be lifted manually and operated, after which it is pushed back down into position.

40 While I have described herein some embodiments of my invention, I wish it to be understood that I do not intend to limit myself thereby except within the scope of the appended claims.

I claim:

45 1. In a cigarette lighter a casing comprising two sections, means pivotally connecting said sections together, a channel-shaped member mounted in the end of one of said sections and extending in a direction perpendicular to the pivotal axis of the connecting means, a cigarette lighter slidably mounted in said channel-shaped member, and means operable upon pivotal opening movement between said sections to move said cigarette lighter into a position for use.

50 2. In a cigarette lighter a casing comprising two sections, means pivotally connecting said sections together, a channel-shaped member mounted in the end of one of said sections and extending in a direction perpendicular to the pivotal axis of the connecting means, a cigarette lighter slidably mounted in said channel-shaped member and having its top surface substantially flush with the surface adjacent the pivotal axis of the sections, and means operable upon pivotal opening movement between said sections to move said cigarette lighter into a position for use.

55 3. In a combined cigarette case and lighter, a cigarette case, a cigarette lighter mounted in said case for sliding movement with respect thereto, a pin fixed in the wall of said cigarette lighter, and a lever pivoted to the case, said lever having a hooked end and engaging beneath said pin, whereby upon opening of the case said lever is raised and lifts the cigarette lighter into a position for use.

4. In a combined cigarette case and lighter, a cigarette case formed of two relatively movable sections, a guide member vertically mounted in one end of one of said sections, a cigarette lighter mounted in said guide member for sliding movement with respect thereto, a pin fixed in the wall of said cigarette lighter, a lever pivoted to the other section, said lever having a hooked end engaging beneath said pin, whereby upon opening movement between said sections said lever is raised and lifts the cigarette lighter into a position for use.

5 5. In a combined cigarette case and lighter, a cigarette case formed of two pivotally connected sections, a guide member vertically mounted in one end of one of said sections, a vertical slot in the inner wall of said guide member, a cigarette lighter mounted in said guide shaped member for sliding movement with respect thereto, a pin extending through said slot and fixed in the 10 wall of said cigarette lighter, and a lever pivoted to the other section adjacent the pivotal axis between the sections, said lever having a hooked end engaging beneath said screw, whereby upon swinging of the second section away from the 15 first section said lever is raised and lifts the cigarette lighter into a position for use.

6. In a combined cigarette case and lighter, a cigarette case formed of two pivotally connected sections, a channel-shaped member vertically mounted in one end of one of said sections, a vertical slot in the inner wall of said channel-shaped member, a cigarette lighter mounted in said channel-shaped member for sliding movement with respect thereto, a screw extending through 20 said slot and threaded in the wall of said cigarette lighter, a lever pivoted to the other section adjacent the pivotal axis between the sections, said lever having a hooked end engaging beneath said screw, and spring means normally urging 25 said lever in the direction of said screw, whereby upon swinging of the second section away from the first section said lever is raised and lifts the cigarette lighter into a position for use.

7. In a combined cigarette case and lighter, a 30 cigarette case formed of two sections having opposite side walls and end, top, and bottom walls meeting along a dividing line, a channel-shaped member vertically mounted in one end of one of said sections, a vertical slot in the inner wall of said channel-shaped member, a manually operable cigarette lighter mounted in said channel-shaped member for sliding movement with respect thereto and having its top flush with the 35 top wall of the casing, a screw extending through said slot and threaded in the side wall of said cigarette lighter, a lever pivoted to the other section adjacent the pivotal axis between the sections, said lever having a hooked end engaging beneath said screw, and spring means normally 40 urging said lever in the direction of said screw, whereby upon swinging of the second section away from the first section said lever is raised and lifts the cigarette lighter into a position for use.

8. A device of the character described comprising a casing having a body portion provided with a space therein for holding cigarettes, a cover movably mounted on said body portion for closing said space, a cigarette lighter, operating means for said lighter independent of said cover, 45 means mounting said cigarette lighter within the casing for movement from an inoperable position within the casing to an operable position in which at least said operating means is outside the casing when the cover is closed, said lighter having 50

a fuel chamber, a wick and igniting means therefor comprising a flint wheel and flint, a flint tube in said lighter for holding said flint, means for holding the flint in said tube, said holding means including a member closing the end of said tube, said casing having an opening therein opposite and adjacent to said closing member when the lighter is in inoperable position within the casing, said member moving away from said opening 10 as the lighter is moved to operable position.

9. In a combined cigarette case and lighter, a cigarette case having relatively movable casing sections, a lighter movably carried by one of said sections and normally inaccessible for operation 15 when said sections are closed, and means operatively connected to the other section and to the lighter and operated directly and positively by relative opening movement between the sections to move said lighter into an operable 20 position at least partially outside the case.

10. In a combined cigarette case and lighter, a cigarette case having relatively movable casing sections, a lighter slidably mounted in one of said sections and normally inaccessible for operation when said sections are closed, and means pivoted to the other section and operatively connected to the lighter and operated directly and positively by relative opening movement between the sections to move said lighter into an operable 30 position at least partially outside the first section.

11. In a combined utility device adapted to be carried on the person, a casing having relatively movable sections, an element slidably guided by one of said casing sections, and a one-way direct 35 and positive connection between the other of said casing sections and said element whereby upon relative opening movement between the sections of the casing to slide said element into a position at least partially outside the case and available 40 for use, said connection being inoperable on the slidable element when the casing sections are relatively moved to closed position, whereby said slidable element may remain in ejected position.

12. In a combined utility device adapted to be carried on the person, a casing having relatively movable sections, an element slidably guided by one of said casing sections, and a one-way direct 45 and positive connection between the other of said casing sections and said element whereby upon relative opening movement between the sections

of the casing to slide said element into a position at least partially outside the case and available for use, said connection being inoperable on the slidable element when the casing sections are relatively moved to closed position, whereby said 5 slidable element may remain in ejected position, and resilient means for holding said slidable element in ejected position.

13. In a combined cigarette case and lighter, a cigarette case having relatively movable casing sections, a lighter movably carried by one of said sections and normally inaccessible for operation when said sections are closed, and means operatively connected to the other section and to the lighter and operated directly and positively 10 by relative opening movement between the sections to move said lighter into an operable position at least partially outside the case, said lighter being movable independently of said last means, whereby the lighter may be moved manually into operable position without opening the casing sections.

14. A combined cigarette case and lighter having front, rear, top, bottom and end walls, said case including casing sections hinged together 25 adjacent said top wall, and a lighter carried by one of said sections adjacent one of said end walls, means mounting said lighter for sliding movement with respect to said section in a direction perpendicular to the axis of said hinge, 30 said lighter having a cover normally flush with said top wall whereby the lighter is inaccessible for operation when said sections are closed, and means operatively connected to the other section and to the lighter and operated directly and positively 35 by relative opening movement between the sections to move said lighter into an operable position at least partially outside the first section.

15. In a device as claimed in claim 14, said cover being pivoted on said lighter to turn about an axis perpendicular to the axis of said hinge, said lighter having igniting means, and means operatively connecting said cover to said igniting means to operate the same when the cover is turned, said lighter moving means moving the lighter to a position where the pivot of said cover is substantially in the plane of said top wall whereby when said cover is turned it strikes the top wall and its movement is limited thereby.

IRVING FLORMAN. 50
